US00D799468S

(12) **United States Design Patent** (10) **Patent No.:** **US D799,468 S**
Chen (45) **Date of Patent:** **** Oct. 10, 2017**

(54) **MOBILE DEVICE PLATFORM**

(71) Applicant: **Lina Zhang**, College Point, NY (US)

(72) Inventor: **ZhenNeng Chen**, ChongQing (CN)

(73) Assignee: **Lina Zhang**, Bayside Hills, NY (US)

(**) Term: **15 Years**

(21) Appl. No.: **29/574,832**

(22) Filed: **Aug. 18, 2016**

(30) **Foreign Application Priority Data**

Apr. 18, 2016 (CN) 2016 3 0129432

(51) **LOC (10) Cl.** **14-03**

(52) **U.S. Cl.**
